Trenton, N.J. 08618

Filed May 8, 1963, Ser. No. 278,825

1 Claim. (Cl. 52—238)

This application is a continuation-in-part of applicant's copending application Serial No. 137,562, filed September 12, 1961, now issued as Patent No. 3,209,869.

This invention relates to partition assemblies and is directed particularly to novel and improved constructions which require no bolts, screws, rivets or other means for erection, except those which may be employed in anchoring the posts of the partition in place. Nevertheless, the assembly is characterized by unusual strength and rigidity while permitting great variations in its form and usage.

As stated in the copending application, many types of partition assemblies have been produced heretofore, but they have in general been relatively expensive to produce and have required numerous bolts, screws, or other fastening means for securing the various elements of the assembly together. As a result, the time and labor involved in erecting prior partitions has been considerable. Moreover, "rail type" partitions, wherein the elements do not extend all the way to the floor or ceiling for support, frequently lack the strength and rigidity desired in many partition assemblies.

In accordance with the present invention, a new type of partition assembly is provided wherein the elements are so formed as to permit interlocking of the elements in a manner which renders it unnecessary to employ bolts or the like in assembling the elements and erecting the partition. However, the elements when thus interlocked so reinforce and mutually support each other as to create a structure which possesses unusual strength and rigidity.

All of the elements employed in assemblies embodying the present invention may be easily fabricated in a factory in standard or usual sizes and lengths and may be varied in their arrangement to produce numerous alternative partition designs to meet widely varying conditions and architectural requirements.

Accordingly, the principal object of the present invention is to provide a novel type of partition assembly adapted to be erected without the use of bolts or other usual fastening means.

Another object of the invention is to reduce the cost and time required to erect partition assemblies.

A further object of the invention is to provide a partition assembly which is characterized by unusual strength and rigidity.

One specific object of the invention is to provide complementary elements for use in erecting partitions, which elements are formed with interlocking means engageable to facilitate erection and cooperate in strengthening and reinforcing each other.

Another and important object of this invention is to provide a snap engagement type of channel member having a wide range of use in the construction and erection of various partition assemblies.

A further important object of the present invention is to provide a partition member with border encasing sheet elements having their ends projecting beyond the end of said partition and having formations on their free ends for snap engagement with complementary formations on another partition element.

Another object of this invention is to provide a partition member with complete encasing sheet elements having their ends projecting beyond the end of said partition and having formations on their free ends for snap engagement with complementary formations on another partition member.

2

Another object of this invention is to provide a partition member formed of a pair of sheet members terminating in transverse flared free ends having formations for snap engagement with complementary formations on another partition member.

These and other objects and features of the present invention will appear from the following description thereof wherein reference is made to the figures of the accompanying drawings.

In the drawings:

FIG. 1 is a detail horizontal section showing a vertical post with a snap engagement type of channel member in engagement therewith, this channel member having channel or groove means for supporting a pane of glass or a panel;

FIG. 2 is a horizontal section of the vertical post shown in FIG. 1 but with the channel member supported by a flat surface of the post and having a partition member attached thereto by means of a pair of short encasing sheet elements provided with snap engagement formations in engagement with complementary formations on said post;

FIG. 3 is a view similar to FIG. 2 but in which the sheet elements may entirely encase the partition member;

FIG. 4 is a view similar to FIGS. 2 and 3 but in which the vertical post is omitted and the channel member is attached to an aligned partition member by screw means;

FIG. 5 is a view similar to FIG. 4 but in which one partition is formed entirely from sheet elements having snap engagement means at their free ends for engagement with complementary means on the channel member; and

FIG. 6 is a detail horizontal section showing an alternative form of sheet encased partition member in which the free ends of the sheet elements are formed for snap engagement with the vertical post shown in FIG. 1.

In that form of the invention shown in FIG. 1, the vertical post 10 is generally H-shaped in cross-section and has parallel face portions 12 joined by an intermediate web 14 to define channels 15 at opposite sides of and opening outwardly from the web, the opposite free edges of each of the face portions of the post being provided with inwardly projecting locking ribs 16 which extend lengthwise of the post. The locking ribs are preferably tapered in cross-section so as to present flat exposed edges 18 and guide surfaces 20 that converge inwardly of the channel toward the web, said guide surfaces terminating in locking surfaces 22 which extend substantially at right angles to the inner surfaces of the respective face portions 12.

A channel member 24 comprises a flat base portion 26 bent at its edges to form longitudinal wing portions 28 extending toward web 14. Wing portions 28 are inclined in conformity to the surfaces 20 of the locking ribs 16 of the post 10 and outwardly offset near their free ends 29 to form longitudinal shoulders 30 at right angles to the longitudinal axis of channel member for snap engagement with the locking surfaces 22 of the locking ribs 16 when the channel member is pressed between the parallel face portions 12. The location of shoulders 30 in spaced relation to the free ends 29, thus, results in the shoulders terminating at convergent offset portions 31, 31 and 33, 33 of the respective wing portions. Portions 31, 31 thus constitute guide surfaces that slide on guide surfaces 20 in response to movement of channel member 24 toward web 14 to interlock shoulders 30 with locking surfaces 22. The embodiment of the channel member shown in FIG. 1 is provided with a central offset portion 32 projecting inwardly between the wings 28 having therein a longitudinal channel or groove 34 for the reception of a pane of glass 36 or a wall panel. For the protection of a pane of glass, the groove may be lined with a flexible gasket 38.

It will be seen from the foregoing description that the post and associated parts illustrated in FIG. 1 correspond to the disclosure in FIG. 10 of my copending application previously referred to. It will also be seen that in order to assemble the channel member 24 with the post 10, it is necessary only to press the channel member laterally between the face portions 12 until the shoulders 30 of the wing portions 28 snap into abutting, locking position against the locking surfaces 22 of the locking ribs 16. Since the post 10 and the channel member 24 when assembled are in telescopic relation, they can be slidably disassembled. The opposite edge of the post may be used to receive another channel member 24 or a panel section as required.

In the form of the invention shown in FIG. 2, the post 10 is the same as shown in FIG. 1. Also the channel member 24a is the same as the channel member 24, except that the groove or channel for a pane of glass is omitted and the channel member is backed against one of the face portions 12 of the post 10 to which it may be welded or rigidly attached thereto by other suitable means. A panel of wall forming material 40 is secured at its upper end between two narrow sheets or strips 42 by screws 44 or other suitable means. The sheets may be of metal or other suitable strong material. They project a short distance beyond the adjacent end of the panel 40 and terminate at their free ends in locking ribs 46 similar to locking ribs 16 of the post 10 and having locking surfaces 48 for snap engagement with the shoulders 30 of the channel member 24a. The panel 40 can be slidably removed from the channel member. Obviously, a similar channel member can be attached to the opposite face portion of the post 10 together with another panel, and similar or varying panels may be snap engaged with the locking ribs 16 of the post 10.

In the form of the invention shown in FIG. 3, the construction and arrangement are identically the same shown in FIG. 2 except that the sheets 42a may encase the entire sides of the panel, which may be desirable in some installations.

In the form of the invention shown in FIG. 4, the panel 40 with the encasing sheets may be the same as shown in FIGS. 2 or 3. The channel member 24b may also be the same as shown in those views except that it is provided at longitudinal intervals with openings 25 for the reception of screws 50 by means of which, or other suitable means, the channel member is attached to another panel 52. This panel may also be encased in sheets 54 of suitable material.

In the form of the invention shown in FIG. 5, the panel 52 together with the attached channel member 24b may be the same as shown in FIG. 4. However, the lower panel 40a is made of two sheets 56 having locking ribs 46a at their ends the same as locking ribs 46 shown in FIG. 4 for snap engagement with the locking surfaces 30 of the channel member 24b. The sheets 56 are bent together below their free ends and secured together by rivets 58 or other suitable means.

In that form of the invention shown in FIG. 6, the panels of wall forming material 60 are provided with a central core or body 62 covered on their opposite faces by sheets of surfacing material 64 which have free edge portions 66 that project beyond the adjacent edge 68 of the body or core 62 of the panels. The surfacing material 64 may be formed of cement, plastic, metal, plywood or other compositions of suitable or desired appearance, strength or weathering properties.

Each of the panels of wall forming material 60 is provided with a channel member 70 which is positioned between the projecting free edge portions 66 of the surfacing material 64 and has a base 72 secured to the edge 66 of the core or body 62 by means of screws 74 or other fastening means. The channel members may be formed as shown at 24 in FIG. 1. In the alternative, as shown in FIG. 6, the channel members 70 may be

provided with opposite sides or wing portions 76 which are inclined inwardly from the opposite sides or ends of the base 72 of the channel member. The extremities 78 of the wing portions of the channel members are then reversely turned, bent or formed to present outwardly projecting locking ribs engageable with the inwardly projecting locking ribs 22 of the H-shaped column 10.

The wing portions 76 of the channel members 70 are thus free to move inward so that the panels may be secured to the column 10 on one side or on opposite sides thereof by pushing the panel toward the column. When the extremities 78 move past the locking lugs 22 on the inner surfaces of the face portions 12 of the column, the wings will spring outward into retaining engagement with the locking ribs on the column 10 to hold the wall forming panel or panels securely in place. However, if desired, the wall forming panels 60 may be assembled with the column 10 by sliding the panel or column longitudinally parallel to the edge 68 of the cores 62 of the panels with the locking ribs and extremities 78 of the channel members in interfitting relation.

With this construction, the free edge portions 66 of the surfacing material 64 of the panels 60 of wall forming material on opposite sides of the column 10 may extend into abutting relation as shown on the lefthand side of the column in FIG. 6. The column itself may thus be hidden or concealed by the projecting free edge portions 66 of the panels to provide a continuous unbroken wall surface. If desired, as shown in FIG. 6, the abutting edges 80 of the projecting portions of the surfacing material 64 may be bevelled as shown at 82 whereby an attractive architectural appearance may be provided while the columns 10 supporting the panels will be completely hidden.

In the alternative as shown on the righthand side of FIG. 6, the adjacent edges 84 of the projecting material 64 of the panels at opposite sides of the partition may be spaced apart to have the area 86 of the face portion 12 of the column visible between the edges of the panels. The face portion may be anodized or colored to present a vertical stripe of contrasting or metallic color which is visible between the edges of the panels for decorative or desired architectural effect or design novelty.

As illustrated in FIGS. 2 to 6 of the drawings, the locking ribs carried by the column 10 and/or the panels may be formed by return bending the ends of the encasing sheets or layers of surfacing material. However, they may be formed by other suitable means as for example, by extrusion or otherwise. Furthermore, the channel members 24, 24a, 24b and 70 shown in FIGS. 2 to 6 are concealed and need not extend the full length of the column but may instead consist of transversely extending straps located in suitably spaced relation lengthwise of the column or panel with the ends thereof reversely turned or formed to engage the locking ribs on the column or panel.

It will be apparent from the foregoing description that the embodiments of my invention shown and described lend themselves to many advantageous variations in the design and construction of partitions with a limited number of types and formations of the elements used in such structures. Also, the elements may be easily assembled in erecting a partition without using any fastening means whatever except those which may be employed in securing an anchor or other element to a floor, ceiling or existing wall. Nevertheless, the partitions produced possess unusual strength and rigidity assuring the requisite durability for any and all installations.

As illustrated in the drawings and described above, the various elements employed in the combination are capable of numerous variations in shape or cross-section. However, in every instance, the elements may be produced in a factory in a form ready for use without modification or change on the site of erection.

While the panels and columns described are particularly

adapted for use in erecting building partitions, they may also be used in other portions of buildings such as walls, curtain walls, and other types of building structures. Moreover, the members to which the panels are connected need not be vertically extending columns, but may be horizontal rails extending along the upper and lower edges of the panel or partition or they may be secured to the floor or ceiling in forming a complete wall section or portion thereof. Thus, if desired, the panels may be provided with marginal elements with locking means thereon extending about the entire perimeter of the panel.

It should, therefore, be understood that the particular form, shape and size of the elements employed and the type of wall-forming sheets, floor anchors and other members used in the assembly and erection of partitions, as shown in the drawings and described above, are intended to be illustrative only and are not intended to limit the scope of the invention.

I claim:

An assembly for partition panels and the like, comprising:

- (a) a vertical post of H-shaped cross-section having
  - (1) parallel face portions, and
  - (2) a web connecting said face portions intermediate the opposite free longitudinal edges of said face portions to define channels at opposite sides of the web opening outwardly therefrom, said edges being formed with inwardly projecting locking ribs extending longitudinally of the post at the opposite sides of each channel, the ribs at the sides of each channel having guide surfaces converging toward the web and terminating in locking surfaces disposed approximately normally to the face portions;
- (b) a vertical channel member for mounting in either of said channels including

5

10

15

30

- (1) a flat base portion disposed parallel to said web and having a longitudinally and centrally extending groove opening away from said web, and
- (2) a pair of longitudinal wing portions extending toward said web from the respective, opposite longitudinal edges of said base portion, said wing portions having outwardly extending shoulders intermediate the ends of the wing portions, said shoulders terminating in convergent offset portions providing guide surfaces, said guide surfaces of the wing portions being slideable along the guide surfaces of the ribs to interlock said shoulders with the locking surfaces of the ribs responsive to movement of the channel member toward the web; and
- (c) a vertical partition panel member extending from the post normally to said web and having an edge portion engaged in said groove of the channel member.
